US00D626952S

(12) **United States Design Patent**
Ding

(10) **Patent No.:** **US D626,952 S**
(45) **Date of Patent:** **** Nov. 9, 2010**

(54) **USB MODEM**

(75) Inventor: **Feng Ding**, Shenzhen (CN)

(73) Assignee: **Huawei Device Co., Ltd.**, Shenzhen (CN)

(**) Term: **14 Years**

(21) Appl. No.: **29/323,538**

(22) Filed: **Aug. 27, 2008**

(30) **Foreign Application Priority Data**

Apr. 17, 2008 (CN) 200830106419

(51) **LOC (9) Cl.** **14-01**

(52) **U.S. Cl.** **D14/242**

(58) **Field of Classification Search** D14/137, D14/140–140.9, 155, 167, 188, 204, 205, D14/207, 210, 215, 218, 230–237, 240, 242, D14/302, 314, 132–134, 348–358, 363, 383, D14/433, 435.1, 496; D13/149, 184, 137.1–139.8, D13/110, 144; 711/100, 115; 361/685, 725, 361/752; 369/272.1, 273, 75.11; 360/133, 360/79.01, 97.03; 379/220.01, 221.09, 220.14, 379/25, 93.09, 93.19, 156, 900, 338–339, 379/441

(57) **CLAIM**

The ornamental design for a USB modem, as shown and described.

DESCRIPTION

FIG. 1 is a bottom view of a USB modem;

FIG. 2 is a right side view thereof;

FIG. 3 is a front view thereof;

FIG. 4 is a back view thereof;

FIG. 5 is a left side view thereof;

FIG. 6 is a top view thereof; and,

FIG. 7 is a front perspective view thereof.

1 Claim, 7 Drawing Sheets

FIG. 1

FIG. 2

FIG. 3

FIG. 4

FIG. 5

FIG. 6

FIG. 7
